Assistant Examiner — Ieisha N Price

(74) Attorney, Agent, or Firm — Greer, Burns & Crain, Ltd.

(57) **CLAIM**

The ornamental design for a rod coupler, as shown and described.

DESCRIPTION

FIG. 1 is a perspective view of the present rod coupler;
 FIG. 2 is a front view of FIG. 1, with the rear view being a
 mirror image thereof;
 FIG. 3 is a top view of FIG. 1;
 FIG. 4 is a bottom view of FIG. 1;
 FIG. 5 is a right side view of FIG. 1; and,
 FIG. 6 is a left side view of FIG. 1.
